COUPLER FOR ROAD SLABS

Robert R. Robertson, Chicago, Ill.

Application July 10, 1940, Serial No. 344,630

4 Claims. (Cl. 94—4)

The present invention relates to concrete road structures and more particularly to couplers or tie units for connecting adjacent concrete road slabs or road lanes to facilitate widening of a concrete road structure by adding road lanes adjacent previously formed road lanes by the use of improved couplers consisting of anchor hooks connected by knuckle joints permitting pivotal movement between the anchor hooks and thereby allowing slight adjustments of adjacent road slabs or lanes with respect to one another without permitting dislocation of adjacent road slabs or lanes with respect to one another.

It is an object of this invention to provide improved coupling units to facilitate the addition of an adjacent road slab or road lane to a previously formed slab or lane by the use of anchoring hooks with adjustable knuckles embedded in the old slab or lane with the knuckles accessible through the side of a slab or lane to permit the engagement of additional anchoring hooks with the knuckles whereby the additional hooks may eventually be embedded in the new concrete poured to form an adjacent slab or road lane.

It is furthermore an object of this invention to provide a road widening mechanism including a channel member embedded in the side of a concrete road lane and housing a plurality of spaced joint knuckles movably engaged on projecting portions of anchoring members embedded in the road lane to form an arrangement whereby additional anchoring hooks may be engaged in the joint knuckles and then be embedded in concrete forming an adjacent road lane so that the additional road widening lane may be coupled to the old road lane and allowing relative movement between the old and new lanes and between the anchoring hooks of the couplers and obviating cracking of the road slab material around the couplers which usually occurs when adjacent road lanes are connected by rigid dowel bars or coupling means.

Another object of the invention is the provision of an improved and simplified form of a road slab coupler consisting of anchoring members for embedding in adjacent slabs and connected to one another by a nut knuckle.

Another object of the invention is the provision of a simplified form of connecting unit consisting of hook members one of which has a combination nut and knuckle pivotally engaged thereon to permit the remaining hook member to be removably engaged with the nut portion of the connector to permit pivotal adjustment of the connected hook members.

It is an important object of this invention to provide a concrete road widening mechanism including a removable road form, a groove forming channel member and a plurality of adjustable couplers each including hook members pivotally connected one to the other by means of a combination knuckle and nut pivotally engaged on one of the hook members within the channel member and accessible when the road form is removed to permit the other hook member to be engaged in the combination knuckle and nut member.

Other and further important objects of this invention will be apparent from the disclosures in the specification and the accompanying drawing.

The invention (in a preferred form) is illustrated in the drawing and hereinafter more fully described.

In the drawing:

Figure 1 is a fragmentary isometric view of a concrete road widening mechanism including improved adjustable couplers embodying principles of this invention.

Figure 2 is an enlarged fragmentary vertical detail section through a concrete road showing the road form still in position with the major portion of a joint coupler embedded in the road slab and showing the position of the remaining hook portion of the coupler in dotted lines to indicate the location of said portion when the road form is removed.

Figure 3 is a fragmentary detail section taken on line III—III of Figure 2 with the concrete and the road form omitted.

Figure 4 is a reduced vertical detail section through a concrete road showing adjacent road slabs or lanes connected to one another by means of an improved coupler partly shown in section and partly in elevation.

Figure 5 is an enlarged top plan view of the coupler knuckle.

Figure 6 is a bottom plan view of the coupler knuckle.

Figure 7 is a perspective view of a modified form of a coupler knuckle.

As shown in the drawing:

In the construction of concrete highways and the like it has been the practice to start the construction by either laying two adjacent lanes simultaneously, or first constructing one lane and then adding additional lanes either on one side or both sides of the previously constructed lane. It often becomes necessary to add additional lanes to either one or both sides of old roads.

In the foregoing method of widening roads considerable trouble has been experienced in that the new lanes or slabs added on the sides of previously formed lanes or slabs very often shift vertically where they abut old sections thereby producing irregularities in the top surface of the widened road and also causing cracking of the road slabs around rigid dowel members which project from one section of the road into another and are flexed by the road slab shifting tendencies to cause damage to the concrete.

The present invention relates to mechanisms for facilitating road widening or slab additions to be made in concrete structures by the use of improved knuckle type couplers embracing separable members adapted to be conveniently assembled for anchoring in adjacent road slabs or road lanes at the same or at different times depending upon when the adjacent slabs or lanes are constructed.

In the present embodiment of this invention the reference numeral 1 indicates a road sub-grade upon which adjacent road slabs or road lanes 2 and 3 are formed at different times. If desired the road lanes 2 and 3 may be separated by a filler or separating strip 4 constructed of plastic or any other suitable material for separating adjacent faces of adjoining slabs or lanes.

It is the intention of this invention to provide a mechanism for conveniently widening a concrete structure such, for example, as a road, to permit additional slabs or lanes to be added to previously formed slabs or lanes. The improved road widening mechanism embraces a road form constructed of metal or other suitable material and briefly comprising a base flange 5 and an integral upright flange 6 adapted to be seated on the road sub-grade previous to the pouring of concrete to form the road slab or lane 2. The road forms are usually used in pairs with the forms positioned on opposite sides of a road bed or sub-grade to define the width of a concrete slab or lane which is to be constructed.

In order to take care of road widening at future dates and provide arrangements whereby additional road slabs or lanes may be constructed adjacent the old slabs or lanes and properly connected thereto, a groove forming channel shield or sheet metal channel member 7 is releasably clamped longitudinally against the outer surface of the vertical flange 6 of the road form by any suitable clamping means temporarily holding the channel member in place during the pouring of concrete. The channel member 7 has the base wall thereof provided with a plurality of spaced slots or openings 8 through which portions of improved road slab couplers are engaged.

When a road slab or road lane 2 is formed so that another road slab or lane may be connected adjacent thereto at a later date, the groove forming channel member 7 for the lane 2 is equipped with the primary portions of improved couplers so that secondary portions of the couplers may be connected thereto at a subsequent time.

Each of the improved couplers forming a part of the road widening mechanism, comprises an open link or double hook anchoring member 9 constructed of a steel or iron rod the ends of which are bent to form an anchoring hook at one end and a supporting hook at the opposite end. The anchoring hook end of the anchoring link 9 is projected through one of the openings 8 in the channel member 7. Pivotally engaged on the supporting hook end of the anchoring link is a knuckle or connecting member comprising a

substantially U-shaped or arched metal head 10 having oppositely positioned notches 11 in the middle portion thereof. Welded or otherwise rigidly secured between the arms of the head 10

5 of the coupler knuckle is a cross-piece or nut 12 provided with a threaded opening 13. The nut 12 formed within the head 10 provides a passage through which the supporting hook end of the anchoring link 9 is adapted to be engaged as 10 clearly illustrated in Figure 3. To complete the coupler an anchoring hook 14 has the threaded end 15 thereof threaded into the opening 13 of the nut 12.

Before the concrete slab or lane 2 is formed and 15 before the channel member 7 is engaged against the road form, a plurality of coupler anchoring links 9 are projected through the openings 8 in the channel member 7 until the knuckles 10 are seated in the channel member 7 as illustrated 20 in Figure 2. The knuckles 10 are shaped complementally to the shape of the interior cross section of the groove forming channel member 7 so that the knuckles may rock in the channel member. With the anchoring members 9 and 25 the knuckles supported thereon engaged with the groove forming channel member 7, said channel member may be placed against the flange 6 of the road form by any suitable removable clamping means, thereby permitting concrete to be poured 30 to form the road slab or lane 2 to embed the major portions of the anchoring members 9 and the channel member 7. After the formation of the slab 2 the road form may be removed thereby exposing the open side of the channel member 35 7 to permit access to be had to the knuckles 10 and the nut portions 12 forming a part thereof.

When it is desired to add an adjacent road slab 3 and connect the same to the road slab 2 for widening the road or concrete structure being 40 formed, it is only necessary to position the compressible filler strip 4 against the side of the slab 2 and then engage the secondary anchoring hooks 14 through the filler strip 4 with the threaded ends of the anchoring members 14 45 threaded into the openings 13 of the nut members 12 of the knuckles seated at spaced intervals in the channel member 7 of the previously formed road section. Attention is called to the fact that with the secondary anchoring members 14 engaging in the nut members 12, the knuckles 10 may be pivoted or rocked either transversely or longitudinally in the channel member 7 and on the supporting hook ends of the primary anchoring members 9, thereby allowing relative longitudinal as well as transverse shifting of the road slabs with respect to one another. With the secondary anchoring members 14 connected with the 50 knuckles seated in the channel member 7 of the previously formed road section 2, the concrete for forming the additional road widening section 3 is poured to embed the secondary anchoring members and to enclose the filler strip 4 between the road slabs 2 and 3 as illustrated in Figure 4.

While the coupler is described as consisting of a knuckle to which the anchoring members are connected to permit pivotal movement of the knuckle and one of the anchoring members with respect to the other anchoring member, attention is called to the fact that the anchoring member engaged with the nut portion of the knuckle may be threaded therethrough into locking engagement with the other anchoring member to thereby lock the anchoring members and the knuckle together to form a rigid structure. This arrangement permits the anchoring member,

threaded into the unit, to be held in place during the pouring of concrete, without requiring a separate support.

Figure 7 illustrates a modified form of coupler knuckle of unitary or one-piece construction and comprising a nut base portion 16 provided with a threaded opening 17 and with a longitudinally disposed passage 18. Integrally formed on the top of the nut portion 16 is a loop-shaped or arched head 19 to permit the knuckle to be engaged on the supporting hook end of an anchoring link or member 9 similar to the arrangement illustrated in Figure 3.

While the improved shiftable or adjustable coupler is illustrated and described in connection with a concrete road widening mechanism in cooperation with a groove forming channel member, it will of course be understood that the flexible knuckle type of coupler may be adapted for various other purposes.

It will furthermore be understood that various details of construction may be varied through a wide range without departing from the principles of this invention, and it is, therefore, not the purpose to limit the patent granted hereon otherwise than necessitated by the scope of the appended claims.

I claim as my invention:

1. A coupling unit comprising a knuckle consisting of a nut portion having a threaded opening therein and an arched portion connected with the nut portion, an anchoring member hooked through the arched portion of the knuckle and pivotally adjustable with respect thereto, and a threaded anchoring member threaded into the nut portion of the knuckle and movable therewith with respect to the first anchoring member, said second anchoring member adapted to be threaded through the nut portion of the knuckle

into engagement with the first anchoring member to lock the anchoring members and the knuckle together to form a rigid construction.

5 2. A road widening mechanism including in combination a groove forming member for temporary engagement against a road form, said groove forming member having spaced slots therein, knuckle members loosely seated in spaced relationship in the groove forming member adjacent the slots, and anchoring members projecting through the slots of the groove forming member and pivotally connected with the knuckle members to hold the knuckle members in position for receiving additional anchoring members

10 15 when it is desired to widen the road.

3. A concrete road widening mechanism including in combination a groove forming member having a row of spaced slots in the longitudinal centerline thereof, a plurality of knuckles having 20 openings therethrough, said knuckles movably seated in the groove forming member adjacent the slots therein, primary anchoring members projecting through the slots in the groove forming member and pivotally engaged through the 25 openings in the knuckles, and secondary anchoring members engaged with the knuckles and pivotally movable therewith with respect to the primary anchoring members.

4. A road widening mechanism including in combination a slotted groove forming channel member, a knuckle movably seated therein and having a passage therethrough, a nut portion in the knuckle, an anchoring member projecting into the slotted channel member and movably engaged 30 through the passage in the knuckle, and a second anchoring member releasably engaged with the 35 nut portion of the knuckle.

ROBERT R. ROBERTSON.
